US00D705442S

(12) **United States Design Patent**
Tipton et al.

(10) **Patent No.:** US D705,442 S
(45) **Date of Patent:** ** May 20, 2014

(54) **LATCH FOR A STERILIZATION CASSETTE**

(71) Applicant: **Hu-Friedy Mfg. Co., LLC**, Chicago, IL (US)

(72) Inventors: **David W. Tipton**, Chicago, IL (US); **Timothy J. Fischer**, Chicago, IL (US); **David K. Platt**, Mount Prospect, IL (US); **Chanel D. Willis**, Munster, IN (US); **Jennifer R. Naylor**, Batavia, IL (US); **Marjavis J. Matthis**, Chicago, IL (US); **Mark Kurth**, Beverly Shores, IN (US); **Timothy Payne**, Chicago, IL (US); **Philip Anthony**, Chicago, IL (US)

(73) Assignee: **Hu-Friedy Mfg. Co., LLC**, Chicago, IL (US)

(**) Term: **14 Years**

(21) Appl. No.: **29/452,322**

(22) Filed: **Apr. 15, 2013**

(51) LOC (10) Cl. **24-01**

(52) U.S. Cl.

USPC **D24/217**

OTHER PUBLICATIONS

Applicant's co-pending Design U.S. Appl. No. 29/424,877, filed Jun. 16, 2012, entitled Sterilization Cassette, Tipton et al.

Primary Examiner — Anhdao Doan

(74) Attorney, Agent, or Firm — Marshall, Gerstein & Borun LLP

(57) **CLAIM**

The ornamental design for a latch for a sterilization cassette, as shown and described.

DESCRIPTION

FIG. 1 is a front view of a latch for a sterilization cassette in accordance with a first embodiment of the present invention;

FIG. 2 is a perspective view thereof;

FIG. 3 is a right side view thereof, the left side view being a mirror image;

FIG. 4 is a top view thereof, the bottom view being a mirror image;

FIG. 5 1 is a front view of a latch for a sterilization cassette in accordance with a second embodiment of the present invention;

FIG. 6 is a perspective view thereof; and,

FIG. 7 is a right side view thereof, the left side view being a mirror image; and,

FIG. 8 is a top view thereof, the bottom view being a mirror image.

The broken lines immediately adjacent the shaded areas represent the bounds of the claim, and all other broken lines are for illustrative purposes only. None of the broken lines form a part of the claimed design.

1 Claim, 2 Drawing Sheets
